United States Patent Office.

STINSON HAGAMAN, OF WEISSPORT, PENNSYLVANIA.

Letters Patent No. 78,959, dated June 16, 1868.

IMPROVEMENT IN MACHINES FOR ROUNDING SLATE-FRAMES.

The Schedule referred to in these Letters Patent and making part of the same.

TO ALL WHOM IT MAY CONCERN:

Be it known that I, STINSON HAGAMAN, of Weissport, in the county of Carbon, and State of Pennsylvania, have invented a new and improved Machine for Rounding and Finishing the Corners of School-Slate Frames; and I do hereby declare that the following is a full, clear, and exact description thereof, which will enable others skilled in the art to make and use the same, reference being had to the accompanying drawings, forming part of this specification, in which—

Figure 1 represents a top view of my improved machine.

Figure 2, a side elevation of the same.

Figure 3, a detached view of the working parts.

Figure 4, the cutter.

This invention relates to a machine for finishing the edges and corners of school-slate frames in an expeditious and handsome manner, and contains a horizontal revolving cutter fastened on the upper extremity of a vertical shaft, against one side of which cutter the edges of the slate-frame may be jointed or finished, whilst the corners are rounded on the other, thereby enabling two persons to work upon the machine at the same time.

This invention consists also in a press, containing a lever and two revolving bolts or centres to hold the corner of the slate-frame firmly, whilst it is gently turned from left to right, causing the frame to come in contact with the revolving cutter.

There is connected with this press an ingeniously-constructed gauge, to stop the slate-frame, so that the revolving bolts or centres may fasten it at the desired place or point.

A represents a rectangular or other frame, made of wood, or other suitable material, of sufficient strength to hold and support the working-parts of this machine.

B is an upright shaft, having its bearings in A, upon which is the pulley C, over which a belt passes to impart motion to the cutter D.

E is a bed-plate of iron, (or any other suitable material,) in which are held two revolving bolts or centres, o o, which are vertically opposite. The lower end of the one underneath rests upon the set-screw F, that the top or face of it may be very accurately adjusted a little above the upper surface of the bed-plate E, that the corner of the slate-frame may rest upon it.

The upper one is pressed down upon the slate-frame by the lever F, thereby forming a very secure fastening to hold the corner of the frame, whilst it is turned about one-fifth of a circle, bringing it at the same time in contact with the revolving cutter, which rounds it off very nicely.

On this bolt there is a loose collar, set-screw, and small coiled-wire spring, to raise it when the lever is released, that the corner of the slate-frame may be easily inserted between the face or head of each bolt o o.

The peg S, that supports the lower bolt or centre and set-screw, is screwed in the bed-plate E, that it may be removed; otherwise, the bolts or centres cannot be inserted in their proper places.

The edges of the cutter D may be straight, concave, or convex, to finish the frames, as desired.

G represents a gauge, made of wood or any other suitable material, on and against which the slate-frames slide when their edges are jointed or finished. This gauge may be adjustable to the cutter as desired.

H is a rocking-tree, I a connecting-rod, and J a short lever, which serves as a gauge to stop the slates at the desired point to be fastened by the press.

This gauge is automatic, or operated by the moving of the slate-frame.

When the corner of the frame is inserted between the bolts or centres, the edge will come in contact with a pin in one arm of the rocking-tree H, holding it even or flush with the projection on the bed-plate at e, which raises the end of the short lever J above the bed-plate to stop the slate at the desired place or point, ready for fastening by the press. When the slate is turned, it relieves the rocking-tree, and causes the lever J to descend below the surface of the bed-plate, and the pin in the rocking-tree to swing to the right, or inside the projection on the bed-plate at e.

Having described my machine, I will explain the difference between it and the one owned by J. W. Sayre and Alexander S. Shull, showing that it is decidedly superior, and that there is no interference between them.

First, it is superior, because it works on a vertical shaft. As two persons can operate on it at the same time, therefore twice the amount of work can be realized.

Second, because I dispense with any vibrating-frame whatever, in which the slate is laid, and clamp to hold them therein, which is all they claim.

Third, because I have no vibrating-frame to operate or weight to raise, merely to turn the slate.

Fourth, because the slates will be held more firmly, as the press fastens the frame close, by the point of contact with the cutter; and, as the press can be operated by the foot, all the power can be applied that is necessary, which is a very essential requirement, as at least five per cent., in my judgment, of the slate-frames are spoiled in rounding the corners with the vibrating-frame, in consequence of their not being held firmly when in contact with the cutter.

What I claim as my invention, and desire to secure by Letters Patent, is—

The bolts or centres O O and lever F, in combination with the rocking-tree H, connecting-rod I, and lever J, all operating substantially as described, and for the purpose specified.

STINSON HAGAMAN.
